UNITED STATES PATENT OFFICE.

FREDERICK R. BISHOP, OF NORTH ATTLEBORO, MASSACHUSETTS, ASSIGNOR TO THE BISHOP COMPANY, INC., OF NORTH ATTLEBORO, MASSACHUSETTS, A CORPORATION OF MASSACHUSETTS.

EYEGLASS-MOUNTING.

1,310,273.

Specification of Letters Patent. Patented July 15, 1919.

Application filed July 8, 1918. Serial No. 243,898.

To all whom it may concern:

Be it known that I, FREDERICK R. BISHOP, a citizen of the United States, residing at North Attleboro, in the county of Bristol 5 and State of Massachusetts, have invented certain new and useful Improvements in Eyeglass-Mountings; and I do declare the following to be a full, clear, and exact description of the invention, such as will enable others skilled in the art to which it appertains to make and use the same.

My invention relates to improvements in eye glass mountings employing what is known as a shell rim and a metal lens holding ring circumscribed thereby. Heretofore, considerable difficulty has been encountered in preventing relative creeping of the ring and rim and for preventing slippage of the several metal clips upon the 15 shell rim, said clips being employed for securing the bows, nose bridge, etc., to the lens carrying means. My invention aims to overcome these difficulties in a simple and inexpensive manner, and with this object in 20 view, the invention resides in the novel features of construction herein shown, described and claimed.

Figure 1 of the accompanying drawing is an elevation of a pair of spectacles 30 constructed in accordance with the invention.

Fig. 2 is a sectional perspective view of the construction employed in mounting the bows.

Fig. 3 is a view similar to Fig. 2 but illustrating the manner in which the nose bridge is mounted.

Fig. 4 is a detail section on the plane indicated by the line 4—4 of Fig. 3.

Fig. 5 is a sectional view through the 40 shell rim and the lens holding ring showing more particularly the peripheral teeth on the latter which embed in the former.

Fig. 6 is a sectional perspective view of a portion of the lens carrying ring.

45 In the drawing above briefly described, the numeral 1 designates what is commonly termed a shell rim, this rim being constructed of tortoise shell, celluloid, or any other preferred material. The rim 1 is 50 either split or continuous according to the style of the glasses and in all cases said rim is provided with an internal channel 2. A metal lens holding ring 3 is snugly received in the channel 2 and is provided on 55 its periphery with suitable teeth 4 which

may be arranged in different ways to be forced into the bottom of the channel, thus serving to a large extent to prevent relative creeping of the rim and ring. The ring 3 is internally channeled at 5 to receive 60 the edges of the lenses 6, and said ring may be either continuous or split as required. In the form of construction shown, both the rim 1 and the ring 3 are split, and on opposite sides of the split, the ring 3 is provided 65 with laterally extending lugs 7 which project into the edges of the shell rim 1, thus effectively retaining the ring within the rim and further preventing possible shifting of the two. A pair of U-shaped metal clips 70 8 embrace the rim 1 adjacent the split portion thereof and carry the usual ears 9 between which the bows 10 are pivoted at 11, said ears being clamped together in the usual manner by screws or the like 12. The edges 75 of the clips 8 are clenched around the edges of the shell rim 1 as seen at 13 and are clenched more deeply at opposite sides of the lugs 7 than over them. By this means, the clenched edges 13 of the clips 8 are formed 80 with shoulders 14 which abut the edges of the lugs, thus positively preventing slipping of the clips upon the ring 1. It will thus be seen that the lugs in question not only 85 positively prevent any relative movement of the shell rim and the metal ring therein, but that they will not permit any sliding of the clips 8 upon the rim. Furthermore, it will be seen that the clenched edges of the clips effectively retain the lugs em- 90 bedded in the edges of the rim.

The nose bridge 15 is provided with clips 8' similar to the clips 8, the edges of said clips 8' being clenched around the edges of the shell rim 1 and being associated with 95 lateral lugs 7' on the ring 3, in the same manner as the lugs 7 and clenched edges 13 are related, and it will thus be seen that slipping of the clips 8' is prevented, and at the same time the lugs 7' serve further to 100 prevent relative shifting of the rim and ring.

From the foregoing, taken in connection with the accompanying drawing, it will be obvious that although my invention is of extremely simple and inexpensive nature, it will be highly efficient and in every way desirable. Since probably the best results are obtained from the details shown and described, they are preferably followed, but 105 110

within the scope of the invention as claimed, considerable latitude is allowed for making such minor changes as occasion may dictate. For instance, the teeth 4 may be of any 5 shape and arranged as required, but in all instances these teeth will be located on the periphery or largest diameter of the ring 3, since by this arrangement, the teeth may be embedded in the shell rim 1 by the simple 10 process of forcing one against the other.

I claim:

1. In an eye glass mounting, a shell rim having an internal channel, a metal lens holding ring in the channel of said shell 15 rim, lateral lugs on the edges of said metal ring projecting into the edges of said shell

rim, and a metal clip embracing the portion of said shell rim into which said lugs project, the edges of said clip being clenched around the edges of said shell rim and being 20 clenched more deeply at opposite sides of said lugs than over them, whereby said lugs prevent the clip from slipping on the shell rim and the latter from creeping on the lens holding ring.

25

2. A structure as specified in claim 1, together with peripheral teeth on said ring embedded in said shell rim.

In testimony whereof I have hereunto set, my hand.

FREDERICK R. BISHOP.
